UNITED STATES PATENT OFFICE.

LEON L. SIBLEY, OF MONROE BRIDGE, MASSACHUSETTS.

MANDREL.

1,296,127.

Specification of Letters Patent.

Patented Mar. 4, 1919.

Application filed July 3, 1918. Serial No. 243,219.

To all whom it may concern:

Be it known that I, LEON L. SIBLEY, a citizen of the United States, residing at Monroe Bridge, in the county of Franklin 5 and State of Massachusetts, have invented certain new and useful Improvements in Mandrels, of which the following is a specification, reference being had to the accompanying drawings.

10 This invention relates to certain improvements in mandrels, and has relation more particularly to a device of this general character especially designed and adapted for use in securing a mill roll of paper to the 15 re-winding shaft or the like and it is an object of the invention to provide a novel and improved mandrel of a construction whereby the same may be readily expanded or contracted in order to effectively engage 20 or release the roll of paper mounted upon a re-winding shaft or the like and without injury to the web.

It is also an object of the invention to provide a novel and improved mandrel divided longitudinally into sections and wherein each of said sections is adapted to be mounted upon a shaft for rotation in unison therewith together with means coacting with the sections of the mandrel for expanding 30 the same.

The invention consists in the details of construction and in the combination and arrangement of the several parts of my improved mandrel whereby certain important 35 advantages are attained and the device rendered simpler, less expensive and otherwise more convenient and advantageous for use, as will be hereinafter more fully set forth.

The novel features of my invention will 40 hereinafter be definitely claimed.

In order that my invention may be the better understood, I will now proceed to describe the same with reference to the accompanying drawings, wherein—

45 Figure 1 is a view partly in elevation and partly in section illustrating a mandrel constructed in accordance with an embodiment of my invention;

Fig. 2 is a sectional view taken substantially on the line 2—2 of Fig. 1; and

Fig. 3 is a sectional view taken substantially on the line 3—3 of Fig. 1.

As disclosed in the accompanying drawings 55 1 denotes a mill roll shaft or the like having its central portion angular in cross

section and its opposite end portions circular in cross section, as indicated at *a* and *b* respectively. One of the portions *b* has affixed thereto through the medium of the pins 3, a sleeve 4. Surrounding the sleeve 4 60 and in longitudinal spaced relation are the annular members or rings 5 fixed to the sleeve 4 through the medium of the pins 3. Loosely mounted upon the sleeve 4, between the annular members or rings 5, is a guide 65 member 6. The periphery of the member 6 is angular in cross section and has its opposite end portions defined by the outstanding flanges 7. By this arrangement it will be perceived that the guide member 6 affords 70 a suitable support for the shaft 1 in a mill roll and without affecting the rotation of the shaft.

The inner end of the sleeve 4 is defined by an outstanding annular flange 8 having 75 its outer side face or its face opposed to the intermediate portion *a* of the shaft 1 provided with an annular recess 9. The inner wall 10 of the recess 9 is beveled or tapered toward the portion *a* and the outer wall 11 80 has its inner face concentric to the adjacent portion *b*. It is to be particularly noted that the outer wall 11 is of a width less than that of the wall 10.

Freely mounted upon the second portion 85 *b* of the shaft 1 is a sleeve 12 having its inner end portion of the same construction as has just been set forth relative to the sleeve 4. Contacting with the outer end of the sleeve 12 is an adjusting member or nut 14 in 90 threaded engagement with the shaft.

The sleeve 4 may be termed a stationary expanding member and the sleeve 12 a movable expanding member. Positioned between the members or sleeves 4 and 12 is a 95 mandrel M split or cut longitudinally to afford two sections 15 and each of said sections 15 is substantially semi-circular in cross section. The opposite ends of the sections 15 of the mandrel M are beveled as at 100 16 to correspond with the beveled side walls 10 at the inner ends of each of the sleeves or members 4 and 12 with the peripheral portion of each of said members 15 at its ends recesses as at 17 to receive the outer 105 wall 11.

Each of the sections 15 of the mandrel M adjacent the ends thereof are provided with the inwardly directed lugs 18 having an opening therethrough conforming to the 110

cross sectional configuration of the portion *a* of the shaft 1 but of increased diameter so that the sections 15 may have lateral movement relative to each other and to the shaft 5 1. Upon turning the adjusting member or nut 14 in proper direction, the same will be caused to force inwardly the expanding sleeve 12, resulting in the expansion of the mandrel M or a relative separating movement of the sections 15 so that said mandrel 10 M may be caused to have effective frictional contact with the wall of the bore of the paper roll through which the shaft 1 and the mandrel M may be directed and which 15 contact is effected without injury to the web of the paper roll or the like.

Disposed through the portion *a* of the shaft 1 at a point in close proximity to the member or sleeve 12, is a pin 19. The pin 20 19 serves as a stop coating with the adjacent lug 18 whereby the sections 15 have limited movement longitudinally of the shaft 1 and a movement only sufficient to permit the mandrel M and the shaft 1 to be withdrawn from a paper roll or the like.

I also find it of advantage to fix to the shaft 1 substantially midway of the portion *b* a collar 20 having its periphery beveled in cross section and on the same angle as 30 the wall 10 of each of the members or sleeves 4 and 12 and extending in the same general direction as the wall 10 of the sleeve or member 4. Secured to the inner face of each of the sections 15 of the mandrel M is an arcuate member or flange 21, having a beveled face riding upon the beveled face of the collar 20. When the sections 15 are expanded to frictionally engage 35 a paper roll or the like, the members or flanges 21 engage the collar 20 at substantially the transverse center thereof, as illustrated in Fig. 1 and whereby the danger of the central portions of the sections 15 being bent inwardly is avoided.

40 45 From the foregoing description, it is thought to be obvious that a mandrel constructed in accordance with an embodiment of my invention is particularly well adapted for use by reason of the convenience and facility with which it may be assembled and operated, and it will also be obvious that my invention is susceptible of some change and modifications without departing from the principles and scope thereof and for this 50 55 reason I do not wish to be understood as limiting myself to the precise arrangement and formation of the several parts herein shown in carrying out my invention in practice except as hereinafter claimed.

60 I claim:

1. In combination with a shaft having an intermediate portion angular in cross section, a mandrel surrounding the intermediate portion of the shaft and split longitudinally into separable sections, each of

said sections being provided adjacent its ends with an inwardly directed lug having an opening substantially conforming to the cross sectional configuration of the intermediate portion of the shaft and through 70 which said shaft is directed, the openings in the lug being of a diameter greater than the diameter of the intermediate portion of the shaft, and expanding members carried by the shaft and coacting with the opposite ends 75 of the mandrel.

2. In combination with a shaft having an intermediate portion angular in cross section, a mandrel surrounding the intermediate portion of the shaft and split longitudinally into separable sections, each of 80 said sections being provided adjacent its ends with an inwardly directed lug having an opening substantially conforming to the cross sectional configuration of the intermediate portion of the shaft and through 85 which said shaft is directed, the openings in the lug being of a diameter greater than the diameter of the intermediate portion of the shaft, and expanding members carried by 90 the shaft and coacting with the opposite ends of the mandrel, one of said members being stationary, and the second of said members being movable longitudinally of the shaft.

3. In combination with a shaft having an intermediate portion angular in cross section, a mandrel surrounding the intermediate portion of the shaft and split longitudinally into separable sections, each of said 100 sections being provided adjacent its ends with an inwardly directed lug having an opening substantially conforming to the cross sectional configuration of the intermediate portion of the shaft and through 105 which said shaft is directed, the openings in the lug being of a diameter greater than the diameter of the intermediate portion of the shaft, expanding members carried by the shaft and coacting with the opposite ends 110 of the mandrel, one of said members being stationary and the second of said members being movable longitudinally of the shaft, and a member threaded upon the shaft for imparting endwise movement to the movable expansion member toward the mandrel.

4. In combination with a shaft having an intermediate portion angular in cross section, a mandrel surrounding the intermediate portion of the shaft and split longitudinally into separable sections, each of 115 said sections being provided adjacent its ends with an inwardly directed lug having an opening substantially conforming to the cross sectional configuration of the intermediate portion of the shaft and through 120 which said shaft is directed, the openings in the lug being of a diameter greater than the diameter of the intermediate portion of the shaft, and expanding members carried 125 by the shaft and coacting with the opposite ends of the mandrel.

by the shaft and coacting with the opposite ends of the mandrel, the inner ends of the members being tapered, the coacting ends of the sections of the mandrel being correspondingly tapered so that movement of one of the expanding members toward the mandrel effects a separating movement to the sections of the mandrel.

5. In combination with a shaft having an intermediate portion angular in cross section, a mandrel surrounding the intermediate portion of the shaft and split longitudinally into separable sections, each of said sections being provided adjacent its ends 10 with an inwardly directed lug having an opening substantially conforming to the cross sectional configuration of the intermediate portion of the shaft and through which said shaft is directed, the openings in 15 the lugs being each of a diameter greater than the diameter of the intermediate portion of the shaft, expanding members carried by the shaft and coacting with the opposite end portions of the mandrel, and 20 means carried by the shaft and coacting with the sections of the mandrel for limiting the movement of said sections in one direction longitudinally of the shaft.

Copies of this patent may be obtained for five cents each, by addressing the "Commissioner of Patents, Washington, D. C."

6. In combination with a shaft having an intermediate portion angular in cross section, a mandrel surrounding the intermediate portion of the shaft and split longitudinally into separable sections, each of said sections being provided adjacent each of its ends with an inwardly directed lug, 30 35 said lug being provided with an opening substantially conforming to the cross sectional configuration of the intermediate portion of the shaft and through which the shaft is directed, the opening in the lug being of a diameter greater than the diameter of the intermediate portion of the shaft, means for imparting separating movement to the sections of the mandrel, and means for limiting the movement of the sections in one direction longitudinally of the shaft.

In testimony whereof I hereunto affix my signature in the presence of two witnesses.

50

LEON L. SIBLEY.
